ELECTRIC DENTAL FURNACE

Börje Féron, Enkoping, Sweden

Application May 1, 1939, Serial No. 271,197
In Sweden November 20, 1937

1 Claim. (Cl. 219—35)

The present invention relates to dental furnaces of the electric resistance type in which the resistance element or heating winding is wound on to an exchangeable body or muffle of fire-proof material, surrounded by an isolating muffle and adapted to be introduced into the isolating muffle from the rear end thereof.

It is a general object of the invention to simplify and improve the construction of dental furnaces of this kind, in order to make the heating muffle easily accessible for inspection and exchange in case of breakage or other disturbances caused by the intense heating of the muffle and associated parts.

15 To this end the resistance winding of the heating muffle is connected to the external connecting terminals through the medium of internal terminal contacts which according to the invention are placed inside the rear end portion of 20 the isolating muffle, but outside the space through which the heating muffle is introduced into the isolating muffle. The internal terminals are adapted to be detachably connected to the resistance windings by means of screws and connecting 25 lugs provided on the heating muffle and are accessible through an opening in the rear end wall of the furnace, through which also the rear ends of the muffles are accessible. Thus by removing the cover, normally closing the opening, 30 access can be had to the interior of the muffles for inspection without affecting the electrical connections. If it is required to remove the heating muffle for repair or exchange this can be effected simply by unfastening the electrical connections at the internal terminals and pulling 35 the heating muffle out through the opening in the rear end wall of the furnace.

The invention will now be described more in detail having reference to the drawing attached 40 to this specification and forming part thereof, in which

Figure 1 shows a vertical longitudinal section through a dental furnace according to one embodiment of the invention.

45 Figure 2 shows the furnace according to Figure 1 in front view,

Figure 3 is a cross section on the line 3—3 in Figure 1, and

Figure 4 is a rear view of the furnace.

50 Referring to the drawing, 1 designates the resistance element which has the form of a ribbon of resistance alloy wound spirally on the inside of an open-ended sleeve-shaped body or muffle 2 of fireproof material, such as steatite or other ceramic material. The width of the ribbon-

shaped resistance winding is preferably ten millimeters and the length thereof ten meters. The ends of the resistance winding 1 are passed through slots provided in the walls of the muffle 2, said ends being welded outside of the muffle 5 each to a connecting lug 3 or 4 respectively, said lug preferably having a width of twenty millimeters and a thickness of two millimeters. The muffle 2 carrying the resistance winding 1 and the connecting lugs 3 and 4 is removably inserted in a sleeve 5 of fireproof and preferably ceramic material, said sleeve extending between the front and rear walls 6 and 7 of the furnace. Provided between the sleeve 5 and the side walls 8 and the bottom 18 of the furnace is heat insulating material 9. The furnace chamber 10 surrounded by the muffle 2 is limited at its rear end by a lid 11 of ceramic material, said lid being removably inserted in the rear end of the muffle and being provided with an opening for the insertion of a pyrometer 12 into the furnace chamber. At the front the furnace chamber is limited by a door 13 adapted to close an opening provided in the front wall of the furnace. The rear furnace wall 7 has an opening through which 15 the muffle 2 can be removed, said opening being adapted to be closed with a detachable lid 14. Between the lid 11 forming the rear wall of the furnace chamber 10 and the lid 14 closing the opening in the rear furnace wall there is formed 20 a space 15 in which the connecting lugs 3 and 4 of the resistance winding of the removable muffle are connected to appertaining leading-in terminals 16 or 17, which are electrically connected with the current source. The space is normally 25 filled by a removable filler body 19 of fireproof material, such as steatite, a disk 20 of asbestos or other soft fireproof material being preferably inserted between the filler body and the lid 14. 30

In the drawing the muffle 2 has been shown 35 as a one-piece body. Preferably, however, the muffle is made in two semicylindrical halves fastened together by means of clay or the like, thereby providing for straight joints which will crack in preference to the material of the muffle proper 40 in case the stresses set up in the muffle during heating should become too high.

The removal of a burnt-out muffle and inserting of a new one is effected in the following manner. First the lid 14 at the rear of the furnace is removed by loosening the four fastening screws of the lid. Thereafter the asbestos disk 20 and the filler body 19 are removed through the opening in the rear furnace wall, whereby access is had 45 to the connecting chamber. The pyrometer 12 50

is then pulled out, whereupon the lid 11 can be removed. After the connecting lugs 3 and 4 have been disconnected from the terminals 16 and 17 the muffle 2 can be pulled out through the opening in the rear furnace wall, whereupon a new muffle with its appertaining heating winding can be inserted in position. The connecting lugs of the new heating winding are then connected to the fixed terminals 16 and 17, the lid 11 with the pyrometer 12 is inserted in the rear end of the sleeve-shaped body or muffle, the filler body 18 and the asbestos disk 19 are placed in position, and finally the opening in the rear wall of the furnace is closed by means of the lid 14, whereupon the furnace is again ready for operation.

I claim:

An electric-resistance furnace comprising, a housing, a resistance winding, an outer muffle of refractory material arranged in said housing,

an exchangeable inner muffle carrying the resistance winding and adapted to be inserted into the outer muffle from the rear end thereof, a closure fitting the rear end of the inner muffle, the end wall of the housing having an opening therein for having access to the interior of the inner muffle, the rear end wall of the housing having an opening therein for having access to the rear ends of the muffles, removable closures for said openings, fixed internal terminals accessible through the opening in the rear wall and located in a free space inside the outer muffle but outside of the space through which the inner muffle is introduced, connecting lugs on the inner muffle, means for connecting said lugs to the internal terminals, and external connecting terminals electrically connected to said internal terminals and secured to the housing of the furnace.

BÖRJE FÉRON.
